METALLIC RECEPTACLE AND CLOSURE
THEREFORWilliam Lockhart, Cleveland, Ohio, assignor to
Cornell Securities Corporation, Cleveland,
Ohio, a corporation of Delaware

Application March 1, 1934, Serial No. 713,460

12 Claims. (Cl. 220—61)

My invention is an improvement in metallic receptacles or containers, and relates more particularly to a closure therefor and means for removably securing a closure in place to effect a fluid-tight seal between the receptacle and the closure.

In shipping metallic receptacles of the full removable head type, it has been found desirable to provide a clamping device by means of which the cover may be clamped in place with only sufficient security to prevent accidental removal thereof in shipment, as for instance, where the empty containers are shipped from the manufacturer to the user. It is also desirable in this event, to apply only sufficient closing pressure to the cover and the gasket separating the cover flange from the bead of the receptacle, to hold the parts together without fully setting or compressing the gasket so that when the receptacle is filled with its charge and the shipper desires to more effectively clamp the cover thereon in a fluid-tight seal, this may conveniently be done by further pressing the cover flange down upon the gasket to compress the latter further against the bead.

It is, therefore, one of the objects of this invention to provide a closing or clamping device for removably securing a cover on a metallic container such as a barrel, drum or the like, to effect a fluid-tight seal between the cover and the receptacle without the aid of tools.

It is another object of the invention to provide means for imparting a closing pressure uniformly along the cover flange and the bead of the receptacle to bring the same together in fluid-tight relation and at the same time to apply such closing pressure throughout a wide range of limits.

A further object of the invention is to seal the cover in place against unauthorized removal.

A still further object of the invention is to construct a clamping device for securing covers on metallic receptacles, which is simple of construction, extremely durable and inexpensive to manufacture and which does not require the use of tools for its operation.

Other objects and advantages of my invention will become more apparent as the following description of two embodiments thereof progresses, reference being made to the accompanying drawings, in which like reference characters are employed to designate like parts throughout the same.

In the drawings, Figures 1 to 6 inclusive illustrate an embodiment of my invention in which

the ring is contracted to press the cover toward the bead of the receptacle, while in Figures 7 to 9 inclusive I have illustrated an embodiment wherein the ring is expanded to force the cover down upon the bead or cover support.

Figure 1 is a top plan view of one embodiment of my invention, showing the cover clamped in place upon a receptacle in fluid-tight sealed relation;

Figure 2 is an enlarged fragmentary section taken on line 2—2 of Figure 1;

Figure 3 is a fragmentary plan view of the adjacent ends of the clamping or locking ring, showing the same contracted to seal the cover on the receptacle. This view shows the operating handle swung to one side, as when the same is not in use for contracting or expanding the ring;

Figure 4 is a view similar to that shown in Figure 3 except that the operating handle is shown in operating position and the adjacent ends of the clamping or locking ring are in ring expanded position so as to permit application of the ring to or removal from the receptacle and its cover;

Figure 5 is a view taken in the direction of line 5—5 of Figure 4;

Figure 6 is an enlarged fragmentary section taken on line 6—6 of Figure 1 and shows one form of ratchet mechanism for contracting and expanding the locking ring;

Figure 7 is a top plan view of a second embodiment of the invention employing a ring which is expanded to press the cover into fluid-tight relation with the receptacle;

Figure 8 is a fragmentary view of the ring in place to press the cover into sealing relation with the receptacle. The ring is shown expanded in solid lines and contracted in broken lines;

Figure 9 is an enlarged section taken on line 9—9 of Figure 8.

While my invention is particularly applicable to metallic containers or receptacles such as barrels, drums and the like, which are provided with a circumferential bead at their open ends for receiving and supporting a cover and for reinforcement purposes, it is to be understood that I do not limit the invention in this respect since the same may be applied to other types of receptacles or containers.

In the accompanying drawings, I have illustrated in Figures 1 to 6 inclusive, one embodiment of the invention and have shown the same applied to a metallic shipping drum 1. The

upper edge of the drum or container is rolled to form a peripheral bead 2 at its open end. A cover 3 comprising a cupped member having a peripheral upwardly and outwardly extending flange 4, is supported by the bead 2 and the packing 5 in such a manner that the cupper portion of the cover may be telescoped for a short distance within the container, as illustrated in Figure 2. It will be noted that a portion of the flange 4 is slightly arcuate in cross section to conform with the approximate curvature of the upper surface of the bead, and that the outer edge of the flange terminates at a point near that defined by the greatest outside diameter of the bead. The packing 5 may consist of an annulus of any suitable packing material such as rubber or cork. I find cork to be very satisfactory in use.

It is desirable that the cover be removably secured on the receptacle in such a manner that a fluid-tight seal between the cover, the packing and the bead may be made.

By means of my invention a fluid-tight seal between these parts is readily accomplished as a further description of the embodiments of my invention shown in the drawings will reveal.

According to the present invention one simple means for removably securing the cover on the receptacle in fluid-tight relation is illustrated in Figures 1 to 6 inclusive and may include a split contractible channeled clamping ring 6 which is substantially U-shaped in cross section and in which the upper and lower flange and bead engaging walls respectively of the ring converge outwardly toward the arched portion such as is indicated more clearly in Figure 2.

Thus it will be seen that by contracting the ring, the cover flange 4 will be pressed tightly against the packing 5 and the supporting bead 2 under a closing pressure exerted thereagainst uniformly throughout the circumference of the ring.

The contractible channeled ring 6 is substantially U-shaped in cross section and is split transversely, preferably at one point as indicated in Figure 1. Lugs 8 extend inwardly from the ring ends defining the split and may be formed integrally with the ring ends or may be formed separately and welded thereto.

In further carrying out the invention I have provided means for contracting and/or expanding the ring about the open end of the receptacle to removably secure the cover in place. Such means, according to the embodiment shown in the drawings, may consist of a bolt or rod 9 having right and left hand threads 10 and 11 respectively, formed thereon from its ends inwardly toward the center, the threaded ends being designed to operate in the respective bearing members 12 and 13 which are internally threaded for that purpose. The bearings 12 and 13 are carried by the lugs 8 and are preferably suspended therebeneath and are movable relative thereto so that in contracting or expanding the ring to its extreme limits, the bearings will not bind on the threaded portions of the bolt 9 due to the decreased or increased diameter of the ring. The bearing members 12 and 13 are therefore pivotally connected as at 14 to the lugs 8.

I have provided means for rotating the bolt 9 in either direction so as to contract or expand the ring as desired and this means may include a ratchet wheel 15 keyed to the bolt 9 as at 16 in Figure 6 for rotation therewith.

The ratchet wheel is provided with a plurality of transverse grooves or sockets 17 which are adapted to receive the dog 18 carried in the ratchet body 19. This is shown more clearly in Figure 6. The ratchet wheel 15 is housed within the body 19 and if the dog 18 were retracted to the dotted line position in Figure 6, the ratchet wheel would be freely rotatable therein.

In Figure 6 the dog is shown in position to 10 rotate the wheel 15 in a counter-clockwise direction when the lever 20 and the body 19 are raised by the operator. Downward movement of the lever and body from the raised position after the wheel has been rotated for about a 15 quarter turn, will permit the dog 18 to be retracted against the compression of the spring 21 due to the bevelled face 22 which engages a wall 23 of the tooth 24. The ratchet body will then be returned to the position shown in full 20 lines in Figure 6 with the further rotation of the ratchet wheel 15, whereupon the dog will enter the next transverse slot 17 and this operation may be repeated until the bolt 9 has been rotated sufficiently in that direction to expand 25 the ring to permit its removal from the drum.

When it is desired to contract the ring after it has been placed in position on the head and drum the operator grasps the end 25 of the dog and retracts the same against the compression of the spring 21 and then turns the shank of the dog approximately 180° in either direction and then releases the same whereupon the projection 26 will be in position to again seat within the depression 27 of the body 19. It will be 35 noted then that the bevelled face 22 of the dog will be reversed and that the upward movement of the ratchet body 19 and the lever 20 will be free since the dog will be retracted in such upward movement due to the bevelled face 22 engaging a wall 28 of one of the teeth 24. Downward movement of the ratchet body and lever 20 will result in a rotation of the ratchet wheel 15 in a clockwise direction, whereupon reversely threaded ends of the bolt 9 will engage the internal threads of the bearings 12 and 13 and will cause the ends of the ring to be drawn together, thus contracting the ring.

The degree of contraction and/or expansion of the ring can thus be controlled by movement 50 of the ratchet body and lever about a horizontal axis and such expansion and/or contraction may be selected by means of the retractible dog 18.

I have provided a lever 20 which serves as an operating handle for the ratchet device and which is attached thereto in any desirable manner such as is indicated at 29 in Figure 6. This lever may be in one piece or may be pivotally attached to the member 30 as at 31. In this manner the lever may be swung in a horizontal plane toward 60 the ring as indicated in solid lines in Figure 1, where the end of the lever may be caused to overlie a tab 32 attached to the ring to permit the usual inspection seal 33 to be wired in place. When the ratchet device is to be operated the lever is swung to the dotted line position in Figure 1 and since it operates on a vertical axis, movement of the lever in a vertical plane for operating the ratchet device can be accomplished without difficulty.

Figures 7 to 9 inclusive are illustrative of a second embodiment of my invention and show the same applied to a clamping ring which is expanded to force or press the cover toward the bead and is contracted to release the cover.

In this embodiment, the drum is preferably formed at its open end in a manner similar to that shown in cross section in Figure 9. The drum upper wall is rolled inwardly and, then outwardly of the drum as at 35 and 36 respectively to provide a cover seat at 37. An annulus of cork or other gasket material 38 is supported on the cover seat to provide a fluid-tight seal between the cover and the seat when the cover is pressed downwardly thereon.

In this form of the invention the cover may comprise a cup-like body 3 having a laterally outwardly extending flat annular flange 39 which overlies the gasket 38 as shown. The drum wall forming the cover seat is then rolled upwardly and again inwardly as at 40 to provide a ring engaging annular flange 41.

The closing ring 42 is split transversely at one point to permit expansion and contraction of the same to press the cover into sealing relation with the open end of the drum or to release the same as the case may be. The ring is wedge-shaped in cross section and engages the top surface of the cover flange and the inner surface 25 of the flange 41, and, when expanded by suitable means, will effectively press the cover into fluid-tight relation with the open end of the drum.

I have found the form of closing means illustrated in Figures 1 to 6 of the drawings can successfully be applied to the present form of the invention and I have thus illustrated the same in connection with Figures 7 to 9. The operation of the ratchet is similar to that already described, and any degree of closing pressure may be applied through the ring. If desired, the ring may only partly be expanded to hold the cover in place as in shipping the empty containers to the user. When the containers are filled the ring may be expanded further to exert strong closing pressure uniformly around the ring to the cover flange.

From the foregoing it will be seen that both embodiments of the invention which I have illustrated and described in detail, will operate to effect a fluid-tight seal between the cover and the open end of the drum, and will permit the cover to be readily applied or removed. Furthermore, by means of this invention, full removable closures for drums or other receptacles are provided which will stand rough handling in use or shipment without danger of leakage. Simplicity of construction and manufacture and low cost also characterize devices made in accordance with this invention.

Various changes in the details of construction and arrangement of parts may be made without departing from the spirit of my invention or the scope of the appended claims.

60 I claim:

1. In a clamping device for a metallic receptacle having a bead rolled about its open end and a cover having a flange fitting over the bead and a packing member between the flange and bead, a transversely split clamping ring engageable with the cover flange and the bead to press the same into fluid sealing relationship with said packing member, and ratchet means for contracting or expanding the ring, said means including a rotatable member connected with the ring ends and means including a pawl for rotating said member in step by step movement.

2. In a clamping device for a metallic receptacle having a bead rolled about its open end and a cover having a flange fitting over the

bead and a packing member between the flange and bead, a transversely split clamping ring engageable with the cover flange and the bead to press the same into fluid sealing relationship with said packing member, a rotatable member connected with the ends of the ring defining the split for contracting or expanding the ring, and means carried by said member for selectively rotating the same in reverse directions, said means including a member movable relative to the rotatable member, a pawl, engageable with the rotatable member and an operating handle.

3. In a clamping device for a metallic receptacle having a bead rolled about its open end and a cover having a flange fitting over the bead and a packing member between the flange and bead, a transversely split clamping ring engageable with the cover flange and the bead to press the same into fluid sealing relationship with said packing member, a rotatable member connected with the ends of the ring defining the split for contracting or expanding the ring, and a ratchet device for selectively rotating said member in reverse directions.

4. In a clamping device for a metallic receptacle having a bead rolled about its open end and a cover having a flange fitting over the bead and a packing member between the flange and bead, a transversely split clamping ring engageable with the cover flange and the bead to press the same into fluid sealing relationship with said packing member, a rotatable member connected with the ends of the ring defining the split for contracting or expanding the ring, and a ratchet for rotating said member in step fashion in one direction.

5. In a clamping device for a metallic receptacle having a bead rolled about its open end and a cover having a flange fitting over the bead, a contractible, channeled clamping ring having portions engageable with and pressing the cover flange and bead together when the ring is contracted, and means for contracting the ring, said means including a member bridging a portion of the circumference of the ring and a ratchet device on said member.

6. In a clamping device for a metallic receptacle having a bead rolled about its open end and a cover having a flange fitting over the bead, a contractible, channeled clamping ring having portions engageable with and pressing the cover flange and bead together when the ring is contracted, and means for contracting and expanding the ring, said means including bearings supported by the ring, a rotatable member operating in said bearings, and means carried by said member and movable relative thereto for rotating the same in either direction, said last named means including a reversible pawl.

7. In a clamping device for a metallic receptacle having a portion rolled about its open end to form a cover seat and a cover having a flange fitting over the said rolled portion, a split channeled clamping ring having portions engageable with and pressing the cover flange upon said seat when the ring is expanded, a rotatable member connecting the ends of the ring and operating in bearings on said ring ends, and a ratchet device for rotating said rotatable member selectively in either direction.

8. In a clamping device for a metallic receptacle having a bead rolled about its open end and a cover having a flange fitting over the bead, a split, channeled clamping ring having portions engageable with and pressing the cover flange

and bead together when the ring is expanded, a rotatable member connecting the ends of the ring and operating in bearings on said ring ends, and a ratchet device for rotating said rotatable member.

9. In a clamping device for a metallic receptacle having a bead rolled about its open end and a cover having a flange fitting over the bead, a split, channeled clamping ring having portions engageable with and pressing the cover flange and bead together when the ring is expanded, and a ratchet operated device connecting the ring ends for expanding the ring, said means including a member bridging a portion 13 of the ring circumference and adjustably associated therewith.

10. In a clamping device for a metallic receptacle having a bead rolled about its open end and a cover having a flange fitting over the bead, a split, channeled clamping ring having portions engageable with and pressing the cover flange and bead together when the ring is expanded, a ratchet operated device connecting the ring ends for expanding the ring, said means 20 including bearings carried by the ring, a rotatable member operating in said bearings, and means carried by said rotatable member for rotating the same in either direction.

11. In a clamping device for a metallic receptacle having a bead rolled about its open end and a cover having a flange fitting over the

bead and a packing member between the flange and bead, a transversely split clamping ring engageable with the cover flange and the bead to press the same into fluid sealing relationship with said packing member, and ratchet means 5 for contracting or expanding the ring, said means including a rotatable member connected with the ring ends and means including a pawl for rotating said member in step by step movement and an operating handle for said ratchet 10 means, said handle comprising hingedly connected sections whereby one section may be swung to an inoperative position toward the circumference of the ring when not in use.

12. In a clamping device for a metallic receptacle having a bead rolled about its open end and a cover having a flange fitting over the bead and a packing member between the flange and bead, a transversely split clamping ring engageable with the cover flange and the bead to press 20 the same into fluid sealing relationship with said packing member, and ratchet means for contracting or expanding the ring, said means including a rotatable member connected with the ring ends and means including a pawl for 25 rotating said member in step by step movement and an operating handle for the ratchet device comprising slidably interfitting sections whereby one of said sections may be moved to an inoperative position when the device is not in use. 30

WILLIAM LOCKHART.
